Primary Examiner — Keli L Hill*Assistant Examiner* — Sara S Sahneh(74) *Attorney, Agent, or Firm* — Novoclaims Patent Services LLC; Mei Lin Wong(57) **CLAIM**

The ornamental design for a digital clamp meter, as shown and described.

DESCRIPTION

FIG. 1 is a front perspective view of a digital clamp meter, showing my new design.

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof, shown in open position. The broken lines in the drawings depict portions of the digital clamp meter that form no part of the claimed design.

1 Claim, 9 Drawing Sheets(56)
